UNITED STATES PATENT OFFICE.

CHARLES C. WIENTGE, OF PROVIDENCE, RHODE ISLAND, ASSIGNOR TO THE HOWARD STERLING COMPANY, OF SAME PLACE.

DESIGN FOR A HANDLE FOR SPOONS, &c.

SPECIFICATION forming part of Design No. 24,767, dated October 22, 1895.

Application filed September 11, 1895. Serial No. 562,212. Term of patent 7 years.

To all whom it may concern:

Be it known that I, CHARLES C. WIENTGE, of the city of Providence, in the county of Providence and State of Rhode Island, have 5 invented and produced a new and original Design for Handles of Spoons and Similar Articles, of which the following is a specification, reference being had to the accompanying drawing, forming part thereof.

10 The drawing represents a handle attached to the bowl portion of a spoon and illustrating my new design, the tine portion of a fork being dotted in position.

15 The leading features of my new design for handles of spoons and similar articles consist in the regular wave-like outline of the handle, broken at intervals by short inwardly-turned convex curves, which gradually increase the width of the handle, these wave-like lines 20 gradually becoming more prominent toward the upper portion, the end of which is finished by inwardly-turned curves meeting a group of lobe-like ornaments, together with surface ornamentation herein shown and described to 25 accentuate the outline.

25 In the drawing, 5 indicates the handle and 6 the bowl portion of a spoon to which the handle is attached. It may, however, indicate the main portion of any similar article, 30 one of which is indicated in the drawing in dotted lines.

The outline of the handle, beginning at the main body of the article, curves boldly outward to 7 7, thence is suddenly contracted by the curves 8 8, then is extended upward and gradually outward to increase the width of the handle by the compound curves 9 9, separated at intervals by the short curves 10 10. From the last or upper curves 10 10 the outline curves boldly outward and then inward 4c to meet the group 11 of lobe-like ornaments in which the central plane portion of the handle converges. The surface ornamentation, to accentuate the outline, consists of successive series of graduated beadings 12 12 and 13 45 13, curving alternately outward and inward and connected by the oppositely-extending scrolls 14 14 and 15 15, the upper scrolls 16 16 being somewhat foliated and carrying graduated beads. Between the ends of these last 50 scrolls is the group 11 of convex lobes, which appear to be extensions of the central panel.

What I claim is—

The design for handles of spoons or similar articles as herein shown and described.

CHARLES C. WIENTGE.
